UNITED STATES PATENT OFFICE

CLAUDE HORTMAN, OF NEW ORLEANS, LOUISIANA, ASSIGNOR, BY MESNE ASSIGNMENTS, TO THE HORTMAN-SALMEN COMPANY, INCORPORATED, OF NEW ORLEANS, LOUISIANA, A CORPORATION OF LOUISIANA

WINDOW FRAME

Application filed December 24, 1931. Serial No. 583,126.

The invention forming the subject matter of this application relates to window frame construction of the usual sliding sash type.

The main object of the invention is to provide a weather proof window frame constructed so as to be readily adapted for use with different forms of building construction such as brick veneer, shingles, stucco, or masonry walls, drop or lap siding.

10 Another object of the invention is to provide a window frame constructed so as to prevent air and moisture seeping from the outside of the building to the inside thereof, and having relatively few parts interchangeable to adapt the frames for use in various types of building construction.

20 A further object of the invention is to provide a window frame construction in which the jambs are connected to the sill so as to eliminate the water trap commonly formed at the ends of the jambs and the parting strip in the frames heretofore in general use.

25 Still another object of the invention is to construct the sill so as to receive a continuous wedge member at its bottom to eliminate the use of loose wedges on the job, and to ensure that the sill remains in position under the impact of blows resulting from the constant raising and lowering of the window sashes.

30 Another object of the invention is to provide a window frame construction in which the outside casing and jambs are connected by a tongue and groove joint covered by a blind stop which takes the place of the ordinary outside casing projection, used to form one side of the groove in which the outside sash ordinarily slides.

40 Still another object of the invention resides in an improved construction between the sill of the frame and the window stool whereby weather is prevented from seeping through the frame from the outside of the 45 sill to the inner walls of the building.

Other objects of the invention will become apparent as the detailed description thereof proceeds.

In the drawings:

50 Figure 1 is a fragmentary perspective view

of one of the jambs of the window frame construction forming the present invention;

Figure 2 is a horizontal section taken on the line 2—2 of Figure 1;

Figure 3 is a fragmentary side elevation 55 of the window sill and the jamb connected thereto, the outside casing being omitted for clearness of disclosure;

Figure 4 is a fragmentary exploded perspective of the window sill, showing the particular form of joint between the lower ends 60 of the jambs and the sills;

Figure 5 is a fragmentary vertical transverse section through the head of the window frame and the trim connected thereto, 65 and illustrating a modification of the window frame construction shown in Figure 1;

Figure 6 is a horizontal section taken through an intermediate mullion of a multiple window frame, constructed in the same 70 manner as that generally disclosed in Figure 5; and

Figure 7 is a vertical transverse section through a window sill constructed in accordance with the present invention.

75 As shown in Figures 1 to 4 of the drawings, the window frame comprises a pair of jambs 1 and 2 (see Figure 4), connected at their lower ends to a sill 3, and at their upper ends to a head 4. The sill 3 is machined 80 out of a single piece of material rabbeted near its inner edge to form a downwardly and outwardly beveled shoulder 5 which is adapted to contact with the correspondingly beveled bottom rail of the inside sash when 85 the latter is lowered in closing position against the sill 3. The shoulder 5 intersects the plane face 6 of the sill; and this plane face continues to a second shoulder 7 formed by a rabbet 8, terminating at the round cornered outer edge 9 of the sill.

The upper narrow face 10 of the sill immediately back of the beveled shoulder 5 is provided with a groove 11 to receive a strip 12 of brass or other suitable material which 95 projects from the upper face 10 into a groove 13 formed in the lower face of a rabbet 14 with which the bottom face of the window stool 15 is provided. From Figure 1 of the drawings, it is evident that the vertical face 100

of the rabbet 14 forms a shoulder seating against the inner face of the sill 4. A packing strip 16 nailed against the inner vertical face of the sill 4 below the stool 15 serves to 5 receive the apron 17 forming a trim finish against the plaster board or other suitable finishing material 18 of the building construction in which the frame is used.

10 The outside of the sill 4 is machined to form an inclined rabbet 19 adapted to receive a wedge shaped strip 20 extending throughout the length of the sill, and seated upon a stud 21 of the wall in which the frame is mounted. This strip 20 forms a solid bottom 15 for the sill 4, and not only prevents the sill from moving or sliding outwardly of the wall but also prevents the sill separating from the lower ends of the jambs 1 and 2 due to the 20 impact of the sashes as they are moved up and down in their guide grooves in the side jambs.

25 The wall in which the frame is mounted is shown as formed by an outer layer of sheathing 22 covered by siding 23. The lower face of the sill 4 is provided with a groove 24 adapted to receive the upper edge of the siding 23 and forms therewith a weather-proof joint to prevent air and moisture leaking into the inside of the building from the outside thereof. The sill has its outer edges rounded off to prevent slivering or denting and the lower face of the sill near the outer edge thereof is provided with a weather drip 30 groove 25. It will be apparent that the sill construction at the lower face thereof provides a perfectly weather tight and solid joint between the sill itself and the wall in which the frame is set.

35 Referring to Figure 4, attention is directed 40 to the fact that the outer edges of the window jambs 1 and 2 terminate a short distance from the shoulder 7 on the sill 4, (see Figure 2). The lower end of the jamb 1 is rabbeted 45 on its front face to form a tongue 26 fitting tightly into the dado 27 formed in the sill 4. The shoulder 28 formed by this rabbet fits, as a lip, closely against the upper face of the sill 4.

50 In the ordinary window frame construction, the dado 27 is made as wide as the jamb is thick, and forms a well having one edge directly open to the weather, with the face of the jamb serving as a means for conducting rain, snow and moisture directly to 55 this edge. This poor construction is usually aggravated by the parting bead groove 30 extending to the bottom of the sill dado, and not being filled by anything, since the parting bead is always stopped against the upper face of the sill. In this invention, the window sill dado is completely filled throughout its length, and the shoulder 28 prevents direct access of moisture thereto.

60 The parting bead groove 30 is less in depth 65 than the shoulder 28, so that the bottom of

groove 30 terminates against the upper face of sill 4 and allows part of shoulder 28 to remain as a protection for the dado joint between the jamb and sill. It will be apparent that this construction completely eliminates the water trap formed at the sill end of the parting bead in a window frame of ordinary construction.

70 The joint between the sill 4 and jamb 2 is exactly the same as the joint between the sill and jamb 1. The same joint is used between the sill and the jambs of any intermediate sash box mullion of a multiple sash frame.

75 The stile 31 of the outside casing has its lower end butted against the horn 32 of the sill 4, and this end is rabbeted to fit over the beveled weather drip shoulder 7 and permit the inner face of stile 31 to contact with the edge of jamb 1. As shown clearly in Figure 2, the edge of the jamb 1 has a bead 33 seated 80 in a groove 34 formed in the back face of the stile 31.

85 The bead 33 is not centered on the edge of the jamb 31; it is located toward the rear face of the jamb so that it extends clear down to the bottom of the dado 27 in the sill 4. Preferably the edge of the bead 33 is flush with the bottom of the shoulder 7 so that when the lower end of stile 31 is rabbeted, the edge of the bead will fit against the stile throughout its length. The sill dado is of the same depth throughout its length; and, preferably, has its bottom flush with the upper sloping surface 8 of the sill between the shoulder 7 and the rounded edge 9, thereby eliminating any weather trap which would occur if the dado were of greater depth.

90 The upper end of the stile 31 has a tongue 35 formed thereon to fit into a groove 36' formed in the lower edge of the head 36 of the outside casing. This casing head 36 extends along the head 4 from one jamb to another of the window frame; and the groove 36' then constitutes a drip groove to prevent water or moisture creeping toward the head 4.

95 The head 4 is of the same width as the jambs 1 and 2; and has one edge provided with a groove, while the other edge has a tongue 38 formed thereon to fit in a groove 39 in the rear face of the casing head 36. The upper edge of the head 36 is squared to seat in a rabbet 40 formed in the lower face of a cap moulding 41, having the usual drip groove 42. The upper face of the moulding 41 is downwardly beveled to shed the weather, and a rib or flange 43 is formed thereon to provide a seat for the lower edge of siding 44 or other finish for the outer wall of the building.

100 The window jamb and head construction vary somewhat with the character of the wall in which the window is to be arranged.

Where the siding 44 is to be directly applied to the studding, as shown for example in Figure 5, the jambs 1 and 2 and the head 4 are each made in one piece. In order to use the same 5 style of outside casing, jambs, sill and head where sheathing 45 is interposed between the studding and the siding, it is necessary to provide for the additional thickness of the finished wall in which the frames are mounted. In order to provide for this additional 10 thickness of the sheathing, the jamb 1 (see Figure 2) has a strip 46 secured to the inner edge thereof. This strip 46 is provided with a tongue 47 fitted into a groove 48 formed 15 on the inner edge of the jamb 1. The strip 46 is also provided with a groove 49 adapted to receive a tongue similar to tongue 47 on a strip similar to strip 46 in cases where it is desired or necessary to use wider jambs; 20 which may be widened merely by securing several edges of strips 46 to the edges of the window jambs. These strips 46 may be continued down past the sill to form a backing for the apron 17. The strip 16 can be used 25 or not, as desired.

A corresponding construction will, of course, be necessary for the head of this type of window frame; that is, a strip 52 similar 30 in cross section to the strip 46 must be nailed or otherwise secured to the inside edge of the head 4, which has its said inside edge similarly grooved to receive the tongue formed on said strip. The cap trim 53 may have its lower edge provided with a tongue 54 adapted 35 to fit into the groove 55 of the strip 52; or to fit into the groove 56 formed on the inner edge of the head 4 to receive the tongue 57 of the strip 52. The tongue 54 is usually omitted; but the groove 55 is always formed 40 in the strip 52 to receive the tongue of a similar strip used to increase the width of the head. A bead 58 may be suitably secured in the rabbet formed by the cap trim and the edge of the strip 56 extending below the 45 groove 55 or groove 56, as the case may be.

The sash bead 58' is used to cover the joint formed between the stiles 59 and the strip 46 of the jamb 1 whenever the strip 46 is omitted. The parting bead 60 is seated in the usual 50 manner in the groove 30 formed in the jamb 1. Attention is directed to the fact that the groove 30 is not sufficiently deep to have the bottom thereof aligned with the face of the tongue 26 at the lower end of the jamb. This 55 construction is provided to eliminate any chance of weather creeping under the end of the stop bead 60 to the joint between the tongue 26 and the dado 27 in the window frame.

60 A particular feature of the invention resides in the arrangement of the adjustable blind stop 62 to cover the joint between the stile 31 of the outside casing and the jamb 1 of the window frame. Of course, it will be 65 understood that the same construction of

blind stop extends along the head of the frame and along the jamb 2 at the other side of the window.

In the form shown in Figures 5 and 6 of the drawings, the strips 46 and 52 are omitted, 70 because in this case the outside sheathing is omitted and the siding is nailed directly to the studding. In order to use the same thickness of sash in this modification of frame all that is necessary is to use a sash bead 63 of different width from the sash bead 58' and corresponding, of course, to the depth of the wall in which the window frame may be placed. In effecting this change, it will be apparent that the same outside casing and the 75 same jambs, head and sill of the window frame may be used. All that is necessary to compensate for the omission of the sheathing 45 and the strips 46 and 52 is to provide sash beading and window sill trim somewhat narrower to compensate for differences in width of the jambs. 80

85 From the foregoing description, it will be apparent that I have provided a substantially weather proof window frame which may 90 be readily adapted for use in walls of different thicknesses. It will also be apparent that I have provided a window frame construction designed to prevent water from feeding back to the head casing or through the jambs or sill 95 to the inside of the wall, or to the inside of the building of which the wall forms a part. The tongue and groove construction is such as to cause each member of the frame to interlock 100 with the other members so that there is only one way in which the frame can be set up exactly square. There is no open joint between the side and head casings of the present frame, since this joint is made weather proof by the tight tongue and groove construction. 105

110 The rabbeting of the lower ends of the jambs to eliminate the ordinary water trap formed by the parting bead groove is one of the most important features of the invention, because it prevents the formation of a well or trap for the water which ordinarily causes the sills to rot at this point and allows the water to be drawn into the house by heat and capillary attraction.

115 The metallic weather strip between the window sill and the stool forms another important element in the prevention of weather leaking through the frame into the interior of the building. The rabbeting of the outside casing at the lower ends forms a water tight 120 joint with the outside weather drip shoulder of the sill. This shoulder also forms a convenient stop against which the lower end of the outside casing may be positioned and nailed. 125

130 The continuous wedge is an essential part of a window frame of this type, because the sill thereof is designed to have the slope about three times as great as that which is normally employed in ordinary window frame con-

struction. Moreover, this wedge forms a solid base to receive the impact of the sashes as they are lowered in the frame, and thereby prevents separation of the sill from the lower ends of the jambs.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim is:

1. In a window frame, a sill having an up-standing portion formed on its upper face and extending along the rear side thereof, a window stool rabbeted to contact with the edge of and seat on said portion, said stool and portion being provided with registering grooves, and a tongue seated in said grooves.
2. In a window frame construction, a sill having a rabbet formed in its lower face between the sides thereof, and a continuous wedge shaped member seated in said rabbet to give the sill a predetermined slope when the lower face of the wedge is seated on a horizontal support.
3. In a window frame construction, a sill, a pair of jambs and a head, and outside casings tongued and grooved to said jambs and head, the head of said outside casings having its lower edge grooved throughout its length to receive tongues on the upper ends of the stiles of said casings and to form a water drip groove between said ends.
4. In a window frame construction, a sill having transverse dados formed therein, a pair of jambs having tongues at their lower ends filling said dados and having shoulders butted against the upper face of said sill, each jamb having a tongue along its outside edge and centered in alignment with the tongues on said ends, outside casings grooved to receive the tongues on said jambs, and blind stops secured to said jambs and the edges of said casings.

50 In testimony whereof I affix my signature.

CLAUDE HORTMAN.
